SYNERGISTIC ANTIOXIDANT COMPOSITIONS

Charles C. Shepherd, Birmingham, Mich., assignor to Ethyl Corporation, New York, N. Y., a corporation of Delaware

No Drawing. Application December 2, 1955
Serial No. 550,786

2 Claims. (Cl. 44—69)

This invention relates to antioxidant compositions and to oxygen-sensitive media containing the same.

It has been found heretofore that 4-(isopropylamino)-diphenylamine is an elegant stabilizer for alkyllead antiknock agents. This compound very effectively inhibits oxidative deterioration of lead alkyls even under severe conditions.

It has also been discovered that 2,6-di-tert-butylphenol has outstanding potency as an oxidation inhibitor for tetraalkyllead antiknock compounds, tetraalkyllead antiknock fluids and stable gasolines such as aviation gasoline and the more modern motor gasolines containing these tetraalkyllead compositions.

It has now been discovered that mixtures of 4-(isopropylamino)-diphenylamine and 2,6-di-tert-butylphenol possess a number of unexpected and important advantages rendering them eminently suited for antioxidant utilities.

An object of this invention is to provide synergistic antioxidant compositions. Another object is to provide particularly effective means for preventing oxidative deterioration of alkyllead antiknock compounds and fluids. A further object is to provide concentrated alkyllead antiknock compositions which are especially stable on storage, even when in contact with oxygen, air or ozone. An additional object is to provide gasoline which is stable against oxidative deterioration. Still another object is to provide leaded gasolines which are stable when in contact with oxygen, air or ozone. Other objects will be apparent from the ensuing description.

The above and other objects are accomplished by providing a synergistic antioxidant composition consisting essentially of 4-(isopropylamino)-diphenylamine and 2,6-di-tert-butylphenol.

This invention has resulted in important advantages in the art of antioxidation. In the first place the compositions of this invention are synergistic in antioxidant function—i. e. in the use of mixtures of 4-(isopropylamino)-diphenylamine and 2,6-di-tert-butylphenol results in a greater than additive effect. This is a very important discovery because it represents a mutual enhancement of antioxidant effectiveness of materials, each of which in its own right is particularly effective as an inhibitor of oxidative deterioration. This discovery is particularly unexpected because it has heretofore been found that antioxidants of various types are not ordinarily cumulative in effect and the effect of a combination of antioxidants of various types cannot be predicted from considerations of the effects of the individual agents when these agents are used alone.

Another advantage of this invention is its widespread applicability. For example, the synergistic compositions of this invention are capable of stabilizing alkyllead antiknock compounds, antiknock fluids containing alkyllead antiknock compounds, unstable gasolines (whether clear or leaded) and stable gasolines containing an alkyllead antiknock compound, the presence of which renders the leaded gasoline susceptible of oxidative deterioration. In

2

these media the synergistic antioxidant effects inherent in the compositions of this invention persist.

One embodiment of this invention is an antiknock composition comprising an alkyllead antiknock compound normally tending to deteriorate in the presence of oxygen and, as a stabilizer therefor, a small stabilizing amount of 4-(isopropylamino)-diphenylamine and 2,6-di-tert-butylphenol. Such antiknock compositions preferably contain a scavenger complement, although this is not essential to this embodiment since it is often desired to store an alkyllead compound in substantially pure state for long periods of time. This aspect of the invention makes this possible by virtually eliminating oxidative deterioration of lead alkyls.

Another embodiment of this invention is gasoline normally tending to deteriorate in the presence of oxygen containing, in amount sufficient to inhibit such deterioration, a small antioxidant quantity of 4-(isopropylamino)-diphenylamine and 2,6-di-tert-butylphenol.

Another embodiment of this invention is leaded gasoline normally tending to deteriorate in the presence of oxygen containing, in amount sufficient to inhibit such deterioration, a small antioxidant quantity of 4-(isopropylamino)-diphenylamine and 2,6-di-tert-butylphenol. In this embodiment the gasoline can itself be inherently unstable in the presence of oxygen or can be a stable gasoline which does not tend to deteriorate in the presence of oxygen containing an antiknock quantity of an alkyllead antiknock compound, the presence of which renders the leaded gasoline susceptible of oxidative deterioration. In this latter medium the synergistic antioxidant compositions of this invention focus their inhibitory action both upon the resulting instability of the normally stable gasoline and upon the alkyllead antiknock compound itself.

In the above compositions of this invention it is preferred to employ 4-(isopropylamino)-diphenylamine and 2,6-di-tert-butylphenol in a weight ratio from between about 9 to 1 to about 1 to 9 respectively because with these ratios the mutual enhancement of antioxidant activity is very pronounced. However, other ratios can be effectively employed.

To prepare the synergistic antioxidant compositions of this invention suitable quantities of 4-(isopropylamino)-diphenylamine and 2,6-di-tert-butylphenol are placed in an appropriate container and mixed. The resulting mixture may be used as such by appropriate blending techniques, although a formulating solvent is usually advantageous.

In the preparation of the improved alkyllead antiknock compositions of this invention the several principal ingredients—tetraalkyllead antiknock compound, scavenger complement (if used), 4-(isopropylamino)-diphenylamine and 2,6-di-tert-butylphenol are introduced into a suitable container and mixed. The order of addition of ingredients during formulation is not critical.

In preparing the improved gasolines of this invention the synergistic stabilizers of this invention are blended in appropriate quantity with the gasoline, the 4-(isopropylamino)-diphenylamine and 2,6-di-tert-butylphenol being used either as a preformed blend or being added separately in either order. If the gasoline is to be leaded the tetraalkyllead antiknock compound or antiknock fluid containing the same can be subsequently blended with this treated gasoline, the antiknock compound or fluid can be added to the gasoline before the synergistic antioxidant composition, the various ingredients of the finished fuel can be blended with the gasoline in various sub-combinations in any sequence or an improved antiknock composition of this invention containing the mixed antioxidants can be blended with the gasoline.

Typical synergistic antioxidant compositions of this invention are presented in Table I.

Table I.—Synergistic antioxidant compositions

4-(Isopropylamino)-diphenylamine, Parts by Weight	2,6-Di-tert-butylphenol, Parts by Weight

10	90
5	95

Representative alkyllead antiknock compositions of this invention are presented in Table II. The figures following the representative ingredients are parts by weight. The two figures following the synergistic stabilizing ingredients show respectively the amounts which are used to obtain a composition containing 0.01 and 2.0 percent by weight of combined stabilizer based on the lead alkyl antiknock agent. The relative proportions of each of the ingredients of this combined stabilizer can be varied as shown in Table I. If the lower figure following the combined stabilizer shown in Table II is increased by a factor of 10, the resulting alkyllead antiknock composition will contain 0.1 percent by weight of the combined stabilizer based on the lead alkyl whereas one-half of the second figure provides a composition containing 1.0 percent. Should other concentrations be desired the proper adjustments are evident.

Table II.—Antiknock fluid compositions

Methyltriethyllead 309.	β,β' -Dibromodiisopropyl ether 130 and β,β' -dichlorodiethyl ether 143.	4-(Isopropylamino)-diphenylamine + 2,6-di-tert-butylphenol.

The antiknock fluid compositions shown in Table II are presented for illustrative purposes only. Other antiknock fluid compositions will now be apparent to one skilled in the art. In all instances the presence of the mixtures of 4-(isopropylamino)-diphenylamine and 2,6-di-tert-butylphenol enhances the stability characteristics of the formulations over those characteristics prevailing in the absence of any stabilizer or when using the same amount of either of the stabilizers separately.

Improved unleaded fuel compositions of this invention are prepared by blending amounts of the synergistic inhibitor compositions of this invention between about 0.001 to about 1 percent by weight in various unleaded gasolines normally susceptible of oxidative deterioration. A wide variety of gasolines can be improved in this manner, for example, gasolines having the following characteristics:

A blend of straight-run catalytically cracked and polymer stocks. Initial boiling point, 98° F.; end point, 402° F. A 100% catalytically cracked gasoline having an initial boiling point of 105° F. and an end point of 425° F.

To prepare the improved leaded gasolines of this invention the improved composite additives shown in Table II are blended in appropriate quantity with unleaded gasolines such as those described above or inherently stable gasolines. If desired, the various ingredients of these composite additives can be blended with such gasolines separately or in sub-combinations.

The ingredients of the synergistic antioxidant compositions of this invention are effective as inhibitors when used alone. The potency of 4-(isopropylamino)-diphenylamine as an alkyllead stabilizer is illustrated by the results of accelerated fluid storage tests. Portions of an antiknock fluid consisting essentially of tetraethyllead, 0.5 theory of bromine as ethylene dibromide and 1.0 theory of chlorine as ethylene dichloride were placed in glass bottles containing 80 percent outage; that is, the bottles contained 80 percent by volume of air. The term "theory" represents the quantity of these halogens theoretically required to react with the lead to form the corresponding lead halide—i. e. two atoms of halogen per atom of lead. Small measured amounts of 4-(isopropylamino)-diphenylamine were added to individual samples of the above antiknock fluid and these samples, together with control samples—i. e., stabilizer-free antiknock fluids—were stored at 50° C. for a period of 168 hours. The amount of fluid decomposition was found by determining the ammonia soluble lead contents of the samples by chemical analysis. Basically, the method involves extracting from the samples all lead salts formed during storage by means of an ammonia-ammonium acetate solution and assaying the amount of such salts in the extract by conventional means. Thus, the method provides a reliable measure of the amount of decomposition which has occurred during the storage test described above. The results are shown in Table III.

Table III.—Stabilization of antiknock fluid with 4-(isopropylamino)-diphenylamine

Conc. of Stabilizer, wt. percent of TEL	Fluid Decomposition, g. Pb per 100 ml. TEL	Reduction in Fluid Decomposition, percent
none	1.94	79
0.03	0.40	97
0.06	0.06	97
0.10	0.06	97
0.20	0.07	96

The results shown in Table III show the outstanding effectiveness of 4-(isopropylamino)-diphenylamine as an

inhibitor for lead alkyl antiknock agents. Considerably inferior results are obtained when the above tests are repeated using the same concentrations of 4-aminodiphenylamine or of diphenylamine.

2,6-di-tert-butylphenol is a particularly effective tetraalkyllead stabilizer. This compound is much more effective than trialkylphenols which have been proposed and used as antioxidants. By way of example, individual gasoline samples containing 3 milliliters of tetraethyllead per gallon as an antiknock fluid consisting essentially of tetraethyllead, ethylene dibromide and ethylene dichloride and containing either 2,6-di-tert-butylphenol or 2,6-di-tert-butyl-4-methylphenol in amount equivalent to 2 pounds per 100 barrels were subjected to storage at 110° F. for 18 weeks. The gasoline used in these tests was a modern motor gasoline which was resistant to oxidation when unleaded. The scavenger complement of these leaded fuels was present in amount such that there were 0.5 theory of bromine and 1.0 theory of chlorine. The amount of antiknock fluid decomposition which occurred during these storage tests was found by determining the alkyllead salt contents of the samples by chemical analysis. These salts were extracted from the gasoline with nitric acid, converted into inorganic lead salts and determined by a spectrophotometric method. The results are shown in Table IV.

Table IV.—Effect of phenolic inhibitors on tetraethyllead decomposition during storage

Inhibitor	Inhibitor Conc., Pounds per 1,000 Barrels	Soluble Alkyllead Salts, mg. per 100 ml.
2,6-Di-tert-butylphenol	2	0.2
2,6-Di-tert-butyl-4-methylphenol	2	0.9

It is obvious from the data in Table IV that 2,6-di-tert-butylphenol is well over 300 percent as effective as 2,6-di-tert-butyl-4-methylphenol in retarding oxidative deterioration of tetraethyllead. Since 2,6-di-tert-butyl-4-methylphenol is representative of 2,4,6-triethyl phenols as a class and possesses an antioxidant potency typical of the class, it is clear that the superior effectiveness of 2,6-di-tert-butylphenol is a distinct technical advantage. Thus, in achieving a synergistic effect between the highly effective inhibitors used in the antioxidant compositions of this invention there is now provided a still further improvement in the art.

To illustrate the unexpected synergistic potency of the compositions of this invention recourse was had to the standard method of the American Society for Test Materials for the determination of the oxidation stability of gasoline (Induction Period Method) ASTM Designation: D-525-46, as fully described in Part III-A, ASTM Standards for 1946. According to this method, the induction period is the period during which there is no drop in pressure indicating no absorption of oxygen, when the test material is placed in a test bomb maintained at a temperature of 100° C. with an initial pressure of 100 pounds per square inch gage of oxygen.

In these tests six different base gasolines were used ranging from a highly unstable gasoline to an essentially oxygen-insensitive gasoline. All of these fuel samples contained 3.0 milliliters of tetraethyllead per gallon as the antiknock fluid described in connection with the preceding series of tests. In Table V, Fuel A was a blend of 90 percent of catalytically cracked and 10 percent of polymer gasoline blending stocks having an induction period (leaded as above) of 115 minutes. Fuel B was a gasoline blend of high olefinic content having an end

point of 390° F. When leaded as above this fuel had an induction period of 215 minutes. Fuels C, D, E and F were commercial motor gasolines having induction periods when leaded of 305, 500, 890 and 925 minutes respectively. Varying concentrations of synergistic antioxidant compositions of this invention were blended with the above gasolines and the induction periods measured. The calculated induction periods were obtained by adding the observed individual induction periods of the two inhibitors when used separately at the concentrations corresponding to their individual concentrations in the mixtures and subtracting the induction period of the leaded gasoline without any inhibitor. The difference between the found or observed induction period and the calculated induction period is known as the induction period increase (IPI) and is a direct measure of the synergistic effect produced by the cooperation between the two inhibitors when used in concert. The results of these tests are shown in Table V.

Table V.—Effect of antioxidants on induction period of leaded gasolines

Fuel	Antioxidant	Antiox- idant conc., lb. per 1,000 bbl.	Induction Period, min.		IPI, min.

	50% 4-IADA-50% DTB	15	2,225	2,107	118

¹ IADA stands for 4-(isopropylamino)-diphenylamine.

² DTB stands for 2,6-di-tert-butylphenol.

Referring to the data shown in Table V it is clear that in all instances a synergistic effect was obtained. The degrees of this mutual enhancement of antioxidant activity were very pronounced. It is pointed out in U. S. Patent 2,160,851 that an induction period of 50 minutes is equivalent to a stabilization under atmospheric conditions and even constant exposure to sunlight for a period in excess of 6 months. Therefore, the induction period increases shown in Table V represent a substantial increase in the useful life of the various leaded fuels.

Generally speaking, the mixed inhibitors of this invention exhibit a larger synergistic effect—i. e. the IPI is greater—when they are used at a concentration in leaded gasoline equivalent to from 10 to about 35 pounds of total inhibitor per thousand barrels of gasoline than when the concentration is equivalent to from about 2 up to 10 pounds per thousand barrels. Consequently, this former concentration range is preferred for use in most leaded gasolines, especially those gasolines which have induction periods from about 100 to about 1200 minutes when containing from about 1 to about 3 milliliters of tetraethyllead per gallon in the absence of an inhibitor.

The results shown in Table V are illustrative of the enhanced stability characteristics of the composition of this invention. Equally good results are obtained with other compositions of this invention such as those described in Table II and unleaded oxygen-sensitive gasolines containing my synergistic antioxidant compositions.

Other advantages of the mixed inhibitors of this invention include freedom from induction system deposit problems; obviation of low temperature varnish and sludge formation on engine parts, such as piston skirts; and water and caustic insolubility, which means that gasoline to which these mixed inhibitors have been added are not deprived of the antioxidant materials upon contact

with water or dilute alkali solutions encountered under refining and storage conditions.

The alkyllead antiknock agents which are stabilized according to certain embodiments of this invention are represented by such compounds as tetramethyllead, tetraethyllead, tetrapropyllead, tetrabutyllead, dimethyl-diethyllead, trimethylbutyllead, and the like, or mixtures thereof. Such compounds containing from 4 to about 16 carbon atoms, one atom of lead and a plurality of lead to carbon bonds, are capable of increasing the octane quality of gasoline when employed therein in antiknock quantities—0.02 to 6.5 grams of lead per gallon. Of such compounds, tetraalkyllead compounds having from 4 to about 12 carbon atoms have superior volatility characteristics from the standpoint of engine induction and are thus preferred. Halogen-containing alkyllead compounds, such as triethyllead bromide, may also be stabilized according to this invention.

The scavengers which are preferably, but not necessarily present in the antiknock fluids and leaded fuels of this invention are organic halide compounds which react with the lead during combustion in the engine to form volatile lead halide. The halogen of these scavengers has an atomic weight between 35 and 80; that is, the active scavenging ingredient is chlorine and/or bromine. Such scavengers include ethylene dibromide, ethylene dichloride; carbon tetrachloride; propylene dibromide; 2-chloro-2,3-dibromobutane; 1,2,3-tribromopropane; hexachloropropylene; mixed bromoxlyenes; 1,4-dibromobutane; 1,4-dichloropentane; β,β' -dibromodiisopropyl ether; β,β' -dichlorodiethyl ether; trichlorobenzene; dibromotoluenes; tert-butyl bromide; 2-methyl-2-bromobutane; 2,3,3-trimethyl-2-bromobutane; tert-butyl chloride; 2,3-dimethyl-2,3-dibromobutane; 2,3-dimethyl-2,5-dibromohexane; 2-methyl-2,3-dibromobutane; 2-methyl-2,3-dichloroheptane; 2-methyl-2,4-dibromohexane; 2,3-dibromopentane; 2,5-dichlorohexane; 3-methyl-2,4-dibromopentane; 1-phenyl-1-bromoethane; 1,2,4-dibromopentane; 1-phenyl-1-chloroethane; ethyl- α -bromoacetate; diethyl-dibromomalonate; propyl- α -chlorobutyrate; 1,1-dichloro-1-nitroethane; 1,1-dichloro-2-nitroethane; 1,1-dibromo-1-nitrobutane; 2-chloro-4-nitropentane; 2,4-dibromo-3-nitropentane; 1-chloro-2-hydroxyethane; 1-bromo-3-hydroxypropane; 1-bromo-3-hydroxybutane; 3-methyl-2-bromo-4-hydroxypentane; 3,4-dimethyl-2-bromo-4-hydroxypentane and, in general, scavengers disclosed in U. S. Patents 1,592,954; 1,668,022; 2,364,921; 2,479,900; 2,479,901; 2,479,902; 2,479,903; and 2,496,983. In short, it is preferred to employ halogenated scavengers containing only carbon and elements selected from the group consisting of hydrogen, bromine, chlorine, nitrogen and oxygen. Particularly preferred scavengers are halo-hydrocarbons, that is, bromohydrocarbons, chlorohydrocarbons and bromochlorohydrocarbons having a vapor pressure of 0.1 to 250 millimeters of mercury at 50° C. The total amount of scavenger used is preferably from about 0.5 to about 2.0 theories, a theory being defined as the quantity required to react with the lead to form lead halide—i. e. 2 atoms of halogen per atom of lead. This amount can be in the form of a single compound or a mixture of compounds. However, when I use mixtures of bromine-containing and chlorine-containing scavengers, particularly bromo- and chlorohydrocarbons as the scavenger complement, I can employ a wider range of concentrations in the proportions described in U. S. Patent 2,398,281. Thus, the scavenger concentrations used are those which are sufficient to control the amount of deposits formed in the engine, particularly on the exhaust valves.

Although 4-(isopropylamino)-diphenylamine and 2,6-di-tert-butylphenol may effectively be associated in the various compositions of this invention in any ratio, I prefer to employ a minimum of 10 percent by weight of either inhibitor in relationship to the total amount of

both inhibitors. In general, suitable amounts of this pair of inhibitors in the leaded and unleaded gasoline embodiments of this invention are between about 0.001 to about 2 percent by weight. These amounts may be varied depending upon the degree of instability of the gasoline and the type of conditions or service to be encountered. In the concentrated alkyllead embodiments of this invention amounts between about 0.01 and about 2.0 percent by weight based on the weight of the alkyllead compound are satisfactory. Again, variations in these amounts are permissible and sometimes advantageous. For example, when the alkyllead antiknock compound or fluid is to be stored for unusually long periods of time under severe oxidizing conditions, higher concentrations of the mixed inhibitors of this invention are useful. Thus, in general the amount of the mixed inhibitors used in the alkyllead antiknock compounds and fluids and clear or leaded gasolines herein described is that which is sufficient to inhibit deterioration of these media when they are placed in contact with air.

The fluid and fuel embodiments of this invention may contain other ingredients, such as dyes for identification purposes; metal deactivators, such as N,N'-di-salicylidene-1,2-diaminopropane, etc.; other antiknock agents, such as the carbonyls of iron, nickel, and like elements, aromatic amines, such as N-methyl aniline, xylidine, etc.; anti-icing and anti-rust additives; surface ignition control additives, such as esters of phosphorus acids; and the like.

The mixed inhibitors of this invention may be blended in the dry state with gasoline or antiknock fluids. However, it is advantageous to employ the mixed inhibitors in the liquid state. This is done by dissolving these mixed inhibitors in a suitable solvent. Particularly suitable solvents include acetone, methylethyl ketone, methanol, ethanol, isopropanol, methyl isobutyl carbinol, benzene, toluene, xylene and the like. In general, ketones and alcohols containing up to about 6 carbon atoms and aromatic hydrocarbons containing from 6 to about 18 carbon atoms are excellent solvents. Not only are such formulations very useful in blending operations because high concentrations of the mixed inhibitors of this invention are soluble therein, but these formulations can be stored for long periods of time without deterioration so long as reasonable storage precautions are taken.

The leaded fuel embodiments of this invention normally contain from about 0.02 to 6.5 grams of lead per gallon although gasolines containing higher concentrations of lead alkyls are also stabilized by employing there-in the synergistic inhibitors of this invention.

Because of the outstanding results achieved from the combination of 4-(isopropylamino)-diphenylamine and 2,6-di-tert-butylphenol this invention has been described in relation to these materials. Good results are obtained by totally or partially replacing 4-(isopropylamino)-diphenylamine in the compositions of this invention with 4-(sec-butylamino)-diphenylamine.

The preparation of 2,6-di-tert-butylphenol is described in U. S. Patent 2,459,597.

4-(isopropylamino)-diphenylamine may be prepared by the reductive alkylation of 4-nitrodiphenylamine with acetone and hydrogen in the presence of a suitable catalyst, such as copper chromite. In practice the reaction is conducted at elevated temperature and pressure using from about 5 to 10 moles of acetone in excess of each mole of 4-nitrodiphenylamine present. Normally, temperatures in the range of about 150 to about 200° C. and pressures in the order of about 500 to about 2000 p. s. i. gauge are used. Among the several methods for the preparation of 4-nitrodiphenylamine is that of condensing aniline with p-chloronitrobenzene.

I claim:

1. Gasoline containing an antiknock quantity of an alkyllead antiknock compound normally tending to de-

teriorate in the presence of oxygen containing, in amount sufficient to inhibit such deterioration, a small antioxidant quantity of a synergistic antioxidant composition consisting essentially of 4-(isopropylamino)-diphenyl amine and 2,6-di-tert-butyl phenol, the weight ratio of 4-(isopropylamino)-diphenyl amine to 2,6-di-tert-butyl phenol being from between about 9:1 to about 1:9 respectively.

2. A leaded gasoline containing from about 1 to about 3 milliliters of tetraethyllead per gallon, said leaded gasoline having an induction period from about 100 to about 1200 minutes, and in amount equivalent to from 10 to about 35 pounds per 1000 barrels of said leaded gasoline, a synergistic antioxidant composition consisting essentially

5

10

of 4-(isopropylamino)-diphenyl amine and 2,6-di-tert-butyl phenol, the weight ratio of 4-(isopropylamino)-diphenyl amine to 2,6-di-tert-butyl phenol being from between about 9:1 to about 1:9 respectively.
